UNITED STATES PATENT OFFICE.

JOSEPH FRADLEY, OF BROOKLYN, NEW YORK.

DESIGN FOR A SPOON-HANDLE.

Specification forming part of Design No. 5,298, dated October 3, 1871.

To all whom it may concern:

Be it known that I, JOSEPH FRADLEY, of Brooklyn, in the county of Kings and State of New York, have invented or produced a new and original Design for a Spoon-Handle; and I do hereby declare that the following is a full, clear, and exact description thereof, which will enable others skilled in the art to make and use the same, reference being had to the accompanying drawing forming part of this specification.

Figure 1 is a front view of a spoon illustrating my improved design. Fig. 2 is a rear view of the same.

My invention has for its object to furnish a neat, simple, and elegant design for a spoon-handle; and it consists in the design hereinafter more fully described.

Across the handle of the spoon, at the base of the upper or wider part of the handle, is formed a transverse beading, A, from which projects shells B, the outer parts of which are flush with the edges of said handle. From the right-hand shell B rises a stem, C, of the lily of the valley, which passes gracefully to the left-hand edge of said handle, along the upper part of which it curves or droops, as shown in Fig. 1. Upon the stem C, as it approaches the left-hand edge of the handle, is formed a large flower, D. From the stem C, a little below the flower D, a branch, E, projects toward the right, and just above its upper end are formed three heads, F, of wheat. For the back of the handle I omit the part of the stem C above the flower D, and the heads F

of wheat above the branch E, as shown in Fig. 2. The handle below the beading A is made round, and slightly tapering to an oval toward the bowl and upper part of the handle of the spoon. Upon the front of the handle, at the point where the handle joins the bowl, is formed a central-pointed rib, having a curved rib upon each side, as shown at the point G in Fig. 1. Upon the rear of the handle, at the point where the handle joins the bowl, are formed branched ribs H, curving from each other, and having a flower, I, similar to the flower D, in the angle between them, as shown in Fig. 2.

I claim as my invention—

1. The design A B C D E for the rear side of the upper part of a spoon-handle, substantially as herein shown and described.
2. The design A B C D E F for the front side of the upper part of a spoon-handle, substantially as herein shown and described.
3. The design H I, in connection with the design A B C D E, for the rear side of a spoon-handle, substantially as herein shown and described.
4. The design G, in connection with the design A B C D E F, for the front side of a spoon-handle, substantially as herein shown and described.

The above specification of my invention signed by me this 2d day of September, 1871.

JOSEPH FRADLEY.
